COMBINED DOOR LOCK AND OPENER

Original Filed Feb. 13, 1929

INVENTOR.

BY *Golten F. Polachek*
ATTORNEY

UNITED STATES PATENT OFFICE

PAUL PELOQUIN, OF BROOKLYN, NEW YORK

COMBINED DOOR LOCK AND OPENER

Application filed February 13, 1929, Serial No. 339,531. Renewed October 23, 1931.

This invention relates to a new and useful device in the nature of a door lock and opener especially adapted for use on motor vehicle doors.

The object of the invention is to provide a door lock and opener which will not only hold the door in a closed position but which will greatly facilitate the opening of the said door, eliminating the ordinary manual exertion of pushing the door free of the door frame when opening the said door.

A further object of the invention is to provide a device of the class described of novel construction and arrangement of parts hereinafter more fully described, claimed and illustrated in the accompanying drawings.

Fig. 1 is a front elevational view of my improved device as viewed from the outside of a door.

Fig. 2 is an enlarged view thereof in an unlocked position as same would appear when viewed from the inside of a door.

Fig. 3 is a similar view to that shown in Fig. 2, showing my improved device in a locked position.

Fig. 4 is a transverse sectional view taken on the line 4—4 of Fig. 3.

Fig. 5 is a similar view taken on the line 5—5 of Fig. 3.

Fig. 6 is a similar view taken on the line 6—6 of Fig. 2.

Fig. 7 is a fragmentary elevational view showing in particular a further development of the door opener member as embodied in my improved device.

Fig. 8 is a front elevational view of the adjusting device as embodied in my improved door lock and opener.

Fig. 9 is a side elevational view thereof.

As here embodied my improved device comprises a case 10 of plate like construction preferably rectangular in shape and having formed therein a plurality of apertures 11 adapted to receive screws, bolts, studs or the like as a means of attaching same to the frame or any convenient, suitable portion of a door. A lock bar 12 is slidably mounted horizontally in brackets 13 and 14, or suitable guides secured to the case 10. The lock bar 12 has formed therein gear teeth 15 adapted to en-

gage similar gear teeth 16 formed in a disc member 17 rigidly secured to a shaft 18. The shaft 18 is rotatively mounted in the case 10 and in a support 19 secured to the outer surface of the case 10. A handle 20 of any desired suitable shape or contour, knob or the like is secured to the outer extended extremity of the shaft 18.

A keeper 21 of rectangular block like construction has formed therein suitable apertures 22 adapted to receive screws, bolts, studs or the like as a means of attaching same to a door jamb in alignment with the case 10, as is customary in ordinary practice. This keeper 21 has formed therein an opening 23 adapted to receive the enlarged extended extremity 24 of the above mentioned lock bar 12.

The above described construction is such as will permit the enlarged extremity 24 of the lock bar 12 to be slidably engaged in the opening 23 formed in the keeper 21 when the door is in a closed position, by means of a partial rotation of the handle 20, for the purpose of holding the door in a locked or closed position. It is understood that the handle 20 is for the locking or unlocking of the door from the outside of the motor vehicle.

An operating lever 25 is pivoted at its lower extremity as at 26 on a pin carried in the case 10, and is provided with an enlarged free extremity 27 or handle element extended somewhat above the case 10. This operating lever 25 engages intermediate a pair of side extended elements 28 and 29 of the above mentioned lock bar 12.

The latter described construction is such as will permit the lock bar 12 to be operated by pivoting or swinging the operating lever 27, for the purpose as above set forth, and so as to provide a means of inside manipulation.

An opener member 30 of bar like construction has formed therein an intermediate elongated aperture 31 adapted to receive the pin 32 secured to the case 10, as a means of slidably mounting the opener member 30 on the pin 31. This opener member 30 is positioned approximately horizontally. The opener member 30 is pivotally mounted at one extremity thereof as at 33 on a pin carried by

the lower extended extremity of the pivoted lever 34. This pivoted lever 34 is pivotally mounted intermediately as at 35 on a pin carried in the case 10. The bell crank 34 is provided with an enlarged upper extended extremity 36 having formed therein an elongated aperture 37 adapted to receive the pin 38 secured intermediately to the lock bar 12.

The opener member 30 is provided with an enlarged extended extremity 34' having a tapered side 35 or surface adapted to engage or strike the tapered side or surface 36 of an opening 37 formed in the keeper 21.

The above described construction is such as will permit the enlarged extremity 34' of the opener member 30 to engage or strike the tapered opening 36 of the opening 37 as above set forth slightly or somewhat after the enlarged extremity 24 of the lock bar 12 has been withdrawn from the aperture 23 formed in the keeper 21 so as to slightly open the door which will free the door from the door frame and permit the door to be readily and easily opened without any exertion or physical strain on the part of the person desiring to enter or leave the motor vehicle.

In Figs. 7, 8 and 9, I have shown the above mentioned opener member constructed of two members 39⁷ and 39, so as to permit the use of a turn buckle having a serrated body 40 or main portion and threaded oppositely extended elements 41 and 42 adapted to engage in suitable threaded openings 43' and 44' formed in the above mentioned members 39⁷ and 39. It is understood that the threaded portions 41 and 42 are left and right hand threaded, as is usual with turn buckles.

A bracket member 43 substantially of plate like construction is slidably mounted in the pins 44 secured to and extended from the holder member 45 of plate like construction. These pins 44 are provided with enlarged extended extremities 46 or heads so as to hold the holder member 43 thereon. Expansion springs 47 are positioned coaxially on the pins 44 as a means of normally holding the bracket member 43 in an outwardly extended position from the holder member 45.

An operating member 48 of cylinder like construction having a serrated periphery 49 is rotatively carried on the pin 50 carried in the lug elements 51 and 52 of the bracket member 43. The holder member 45 has formed therein an enlarged opening 53 adapted to freely receive the operating member 48. This holder member 45 has also formed therein a plurality of apertures 54 adapted to receive, screws, bolts, studs or the like as a means of attaching the holder member 45 to any suitable convenient portion of the case 10.

The latter described construction is such as will permit the serrated periphery 49 of the operating member 48 to engage the serrated body 40 of the turn buckle when the oper-

ating member 48 is manually pressed or urged inwardly as a means of manipulating the turn buckle for the purpose of correctly positioning the enlarged extremity 34' of the opener member so as to provide a more effective and efficient device.

A suitable spring 25' is provided for keeping the door lock in normally closed position.

It is understood that my improved device may be used on any door such as safe doors, doors of buildings, etc.

While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new and desire to protect by Letters Patent of the United States is as follows:

1. In combination with a door lock of the class described, a door opener comprising an opener member having formed therein an intermediate elongated aperture adapted to receive a pin secured to the case of the said device, as a means of slidably mounting the said opener member on the said pin, said opener member pivotally mounted at one extremity thereof on a pin carried by the lower extremity of a pivoted lever, said pivoted lever pivotally mounted intermediately on a pin carried in the said case, said pivoted lever operatively connected to the mechanism adapted to operate the said door lock, the said opener member provided with an enlarged extremity adapted to engage in an opening formed in a catch member as a means of partially opening the said door, an operating member as a means of adjusting the said opener member, said operating member comprising a cylindrical member having a serrated periphery rotatively mounted on a bracket member, said bracket member normally held in an extended position from a holder member by means of expansion springs coaxial on pins secured to and extended from the said holder member.

2. In combination with a door lock of the class described, a door opener comprising an opener member having formed therein an intermediate elongated aperture adapted to receive a pin secured to the case of the said device, as a means of slidably mounting the said opener member on the said pin, said opener member pivotally mounted at one extremity thereof on a pin carried by the lower extremity of a pivoted lever, said pivoted lever pivotally mounted intermediately on a pin carried in the said case, said pivoted lever operatively connected to the mechanism adapted to operate the said door lock, the said opener member provided with an en-

larged extremity adapted to engage in an opening formed in a catch member as a means of partially opening the said door, said opener member being adjustable by a turn buckle having peripheral teeth, an operating member as a means of adjusting the said opener member, said operating member comprising a cylindrical member having a serrated periphery rotatively mounted on a bracket member and engageable with said teeth, said bracket member normally held in an extended position from a holder member by means of expansion springs coaxial on pins secured to and extended from the said holder member.

3. In combination with a door lock of the class described, a door opener comprising an opener member having formed therein an intermediate elongated aperture adapted to receive a pin secured to the case of the said device, as a means of slidably mounting the said opener member on the said pin, said opener member pivotally mounted at one extremity thereof on a pin carried by the lower extremity of a pivoted lever, said pivoted lever pivotally mounted intermediately on a pin carried in the said case, said pivoted lever operatively connected to the mechanism adapted to operate the said door lock, the said opener member provided with an enlarged extremity adapted to engage in an opening formed in a catch member as a means of partially opening the said door, an operating member as a means of adjusting the said opener member, said operating member comprising a cylindrical member having a serrated periphery rotatively mounted on a bracket member, said bracket member normally held in an extended position from a holder member, resilient means serving to hold said bracket member in the extended position.

In testimony whereof I have affixed my signature.

PAUL PELOQUIN.
